UNITED STATES PATENT OFFICE.

MICHAEL H. HICKEY, OF CHICAGO, ILLINOIS.

HANDRAIL GUARD.

Application filed December 12, 1921. Serial No. 521,723.

To all whom it may concern:

Be it known that I, MICHAEL H. HICKEY, a citizen of the United States, residing at Chicago, in the county of Cook and State 5 of Illinois, have invented certain new and useful Improvements in Handrail Guards, of which the following is a specification, reference being had to the accompanying drawings, and to the reference characters 10 marked thereon, which form a part of this specification.

My invention relates to porch and stair rail guards, and more particularly to means for securing the rail of the porch or stairs 15 to a pillar or post.

In the ordinary construction of porch and stair rails, the end of the rail abuts the side of the post and the two are secured together by toed nails. In a comparatively short 20 time, the joint between the rail and the post will ultimately open sufficiently to receive and collect moisture, causing decay of the contiguous portions of the wood, the rusting of the nails, and a disassociation of the parts. 25 The results of this trouble are not always visible and consequently serious accidents have occurred where persons have taken hold of, or leaned up against a porch or stair rail thus deteriorated, and found that the rail 30 gave way under the strain.

The principal object of my invention, therefore, is to provide a metal connection between the hand rail and the post, which will firmly resist outward or lateral strains 35 on the hand rail. Another object of my invention is to provide a rail end guard of such form that it may be used "on the job" for various applications, by the mere bending of the same, thus obviating the necessity of 40 the contractor or carpenter carrying "in stock" a large assortment of vari-shaped devices.

To the accomplishment of the aforesaid objects, I have provided a flat, relatively 45 wide supporting plate on which the hand rail will rest, and an upright flange secured to said plate on that side or margin where it will best serve to resist lateral strain. I have also provided the device with a pin 50 adapted to enter the post, and a flexible connection between the pin and the supporting plate; all of which will more fully appear as I proceed with my specification.

In the drawings:

Fig. 1 is a side elevation of a portion of a

porch rail with my improved guard in position.

Fig. 2 is a similar view of my guard, to which a stair rail is attached.

Fig. 3 is a view looking downward, as indicated by the arrows in Fig. 1, the supporting post being in section.

Fig. 4 is a vertical sectional view, taken in the plane indicated by the dotted line 4-4 of Fig. 3.

Fig. 5 is a plan view of one of my guards, detached.

Fig. 6 is a view in perspective, of one of the guards.

Fig. 7 is a plan view of a modified form of the guards.

In the form in which I have chosen to illustrate my invention in said drawings, A represents the guard as a whole, the same comprising three essential parts: namely, 75 a pin or tenon 1, a bearing plate 2 and a lateral-strain resisting flange member 3. The pin or tenon 1 will be of such diameter and length as to be forced into a suitable opening in an upright or post 4. The plate 80 2 will be, preferably, wide and flat to receive the straight surface of a hand-rail 5 of a porch, as shown in Figs. 1 and 3. It will be of such thickness as may be required to sustain the load upon it. The supports A 85 are made rights and lefts,—that shown in Figs. 1, 2, 3, 4, 6 and 7 being a right hand guard and that shown in Fig. 5 a left hand guard.

The plate 2 and the pin or tenon 1 are 90 connected by a shank member 6. In that form of the device wherein the hand rail 5 extends at right angle to the post 4, the shank 6 will be in prolongation of and in substantially the same plane as the plate 2. 95 In that use, where the hand rail 5 extends at an angle to the post 4 as in the case of the stair rail shown in Fig. 2, the shank member 6 will be bent sufficiently to make the angle of the plane of the plate 2 coincident with 100 the angle of the hand rail 5. This can readily be done "on the job" by the carpenter or contractor.

7 is a bolt hole punched through the plate 2 by means of which the rail 5 will be secured to the plate 2 by means of the bolt 8 and nut 9.

It will be noticed that the parts 1, 2, 3 and 6 are integral. In Fig. 7, however, I have shown a modification, in this, that the parts 110

are not integral. It may be convenient to provide the pin or tenon 1 with a relatively small plate 2 and to provide a second plate 2^a having an upturned thrust-resisting flange 3 on one margin, and to secure the two plates 2 and 2^a together by spot welding or any other suitable means. In this construction, the two parts would be preferably secured together before being placed 10 in the hands of the ultimate user, and the bolt aperture 7 punched through both plates.

In practice, the carpenter will first bore a hole in the upright post 4 suitable for receiving the pin or tenon 1. He will then force the pin or tenon in proper position, using a right or left hand guard A, as the particular job requires. He will then place the hand rail 5 in juxtaposition, and having 20 previously bored through the rail a bolt aperture corresponding to the aperture 7, will then insert the bolt 8 and secure it to the rail and the guard A together, by means of the nut 9. The end of the rail 5 may 25 then be nailed to the post or upright 4 in the usual manner, although it will be found that such strain as is placed upon the rail 5 will be a lateral strain rather than a longitudinal one. Such strain will bear first 30 against the upright flange 3 and be transferred through the plate to the pin or tenon 1, where of course it will be absorbed by the resistance of the upright 4. In other words, the rail will be firmly held in position 35 against lateral displacement by means of the construction shown.

The device is simple, cheap to manufacture, and has no parts to get out of order. It possesses great utility and durability in 40 use.

I have shown the pin 1, as round and with a square end. This is the preferred construction but there is no objection to pointing the end nor roughening the surface, similar to the familiar lag-screw or otherwise.

I claim as my invention:

1. In combination with a support, and a rail secured thereto, of additional means for preventing separation of said rail from said support comprising a member secured to said rail and provided with a flange adapted to contact the side of said rail and having an element extending into an aperture in said support, substantially as described. 55

2. In combination with a support, and a rail secured thereto, of additional means for preventing separation of said rail from said support comprising a member having its body portion secured to the bottom of said rail and an integral flange projecting upward from said body portion to contact a side of the rail and an integral tenon extending into an aperture in said support, substantially as described. 60

65 3. As a new article of manufacture for use as a guard for preventing separation of rails from their supports, comprising a flat plate adapted to be secured to the base of the rail, an integral flange adapted to contact a side of the rail and an integral tenon located in the same plane as the plate adapted to extend into the support. 70

75 4. As a new article of manufacture for use as a guard for preventing separation of rails from their supports comprising a flanged plate adapted to be secured to the base of the rail to embrace a side thereof, and provided with a tenon adapted to extend into the support, the juncture of said 80 tenon and plate being so formed as to permit said tenon to be distorted for attachment to rails of different angular inclination.

In testimony, that I claim the foregoing 85 as my invention I affix my signature, in the presence of two witnesses, this 30th day of November, 1921.

MICHAEL H. HICKEY.
